UNITED STATES PATENT OFFICE.

BONA ALLEN, JR., OF BUFORD, GEORGIA.

TANNING-DRUM.

SPECIFICATION forming part of Letters Patent No. 756,554, dated April 5, 1904.

Application filed September 8, 1903. Serial No. 172,388. (No model.)

To all whom it may concern:

Be it known that I, BONA ALLEN, Jr., a citizen of the United States, residing at Buford, in the county of Gwinnett and State of Georgia, have invented certain new and useful Improvements in Tanning-Drums; and I do hereby declare the following to be a full, clear, and exact description of the invention, such as will enable others skilled in the art to which it appertains to make and use the same.

My invention relates to an improvement in tanning-drums; and the object of my invention is to provide a simple and inexpensive device of this class and one from which the racks or frames supporting the hides may be easily and quickly removed.

With these objects in view my invention consists in the construction and combinations of parts, as hereinafter described and claimed.

In the accompanying drawings, Figure 1 represents a side view of my invention, partly in section. Fig. 2 represents a cross-section of the same; and Fig. 3 represents a plan view of one of the supporting racks or frames, showing in dotted lines a hide stretched thereon.

a represents a drum provided with a cover fastened thereto by hinges *b*. The cover is removably held in place by any suitable fastening means, such as a link *c* and eyelet *d* and a pin *e*. The drum is supported on shafts *f* and *g*, attached to the outside thereof, which shafts are supported in a suitable frame.

h represents a pulley used for driving the drum. To each end of the drum are fastened parallel guides *i* and *j*, between which the hide-supporting frames are adapted to be guided and held. The frames themselves consist of end pieces *k* and cross slats or wires *l*. The end pieces *k*, as shown in Figs. 1 and 2, are considerably thicker than the slats, so that when the frames are piled up one above another the slats are separated from each other by a short distance.

In the use of my invention the cover of the drum is opened and the frames, with a hide fastened to each one, are lowered into the drum between the guides *i* and *j* until as many frames have been placed in the drum as the latter will hold. Tanning liquor is then run into the drum and the hinged door closed and fastened. The drum is then revolved in either direction for a sufficient time to effect the tanning.

I prefer to fasten the hides on the frames in opposite directions, as shown by the dotted lines at the top and bottom of Fig. 2. This causes a circulation of the liquor around the hides no matter which direction the drum is revolved in. After the tanning operation is finished the hinged door is opened and the frames, with the hides attached thereto, lifted out one by one for further treatment.

Having thus described my invention, what I claim as new, and desire to secure by Letters Patent, is—

1. In a tanning-drum, the combination of the drum proper, guides secured thereto, and hide-carrying frames adapted to be slipped in, one above the other between said guides, forming a column of frames superposed above each other, substantially as described.

2. In a tanning-drum, the combination of the body of the drum, provided with a hinged door, guides secured at each end of said drum, and hide-carrying frames adapted to be slipped down between said guides, and held in position by said guides and the periphery of said drum, substantially as described.

3. In a tanning-drum, the combination of the body of the drum, provided with a hinged door, and the ends thereof provided with guides arranged parallel to each other, of hide-carrying frames adapted to be slipped in between said guides, said frames being provided at their ends with spacing means, substantially as described.

4. In a tanning-drum, the combination of the body of the drum, provided with a hinged door, the ends of the drum provided with parallel guides, means for fastening said hinged door in a closed position, with removable frames adapted to be slipped down between said guides and held in position by the periphery of the drum, each of said frames being provided with spacing means at its ends, and means for supporting and revolving said drum, substantially as described.

In testimony whereof I affix my signature in presence of two witnesses.

BONA ALLEN, JR.
